CLAIM

The ornamental design for an instrument case, as shown and
 described.

DESCRIPTION

FIG. 1 is a front elevational view of an instrument case in
 accordance with a first embodiment of the present invention;
 FIG. 2 is a rear elevational view of the instrument case
 illustrated in FIG. 1;

FIG. 3 is a right side elevational view of the instrument case
 illustrated in FIG. 1;

FIG. 4 is a left side elevational view of the instrument case
 illustrated in FIG. 1;

FIG. 5 is a top plan view of the instrument case illustrated
 in FIG. 1;

FIG. 6 is a bottom plan view of the instrument case
 illustrated in FIG. 1;

FIG. 7 is a plan view of the instrument case illustrated in
 FIG. 1, showing the instrument case in an open position;

FIG. 8 is a front elevational view of an instrument case in
 accordance with a second embodiment of the present invention;

FIG. 9 is a rear elevational view of the instrument case
 illustrated in FIG. 8;

FIG. 10 is a right side elevational view of the instrument
 case illustrated in FIG. 8;

FIG. 11 is a left side elevational view of the instrument case
 illustrated in FIG. 8;

FIG. 12 is a top plan view of the instrument case illustrated
 in FIG. 8;

FIG. 13 is a bottom plan view of the instrument case
 illustrated in FIG. 8;

FIG. 14 is a plan view of the instrument case illustrated in
 FIG. 8, showing the instrument case in an open position;

(Continued)

FIG. 15 is a front elevational view of an instrument case in accordance with a third embodiment of the present invention;

FIG. 16 is a rear elevational view of the instrument case illustrated in FIG. 15;

FIG. 17 is a right side elevational view of the instrument case illustrated in FIG. 15;

FIG. 18 is a left side elevational view of the instrument case illustrated in FIG. 15;

FIG. 19 is a top plan view of the instrument case illustrated in FIG. 15;

FIG. 20 is a bottom plan view of the instrument case illustrated in FIGS. 15; and,

FIG. 21 is a plan view of the instrument case illustrated in FIG. 15, showing the instrument case in an open position.
